UNITED STATES PATENT OFFICE.

MILTON F. WILLIAMS, OF ST. LOUIS, MISSOURI, ASSIGNOR TO WILLIAMS PATENT CRUSHER & PULVERIZER COMPANY, A CORPORATION OF MISSOURI.

ADJUSTING MECHANISM FOR CRUSHERS OR PULVERIZERS.

1,039,623.

Specification of Letters Patent. Patented Sept. 24, 1912.

Application filed August 4, 1911. Serial No. 642,299.

To all whom it may concern:

Be it known that I, MILTON F. WILLIAMS, a citizen of the United States, residing at St. Louis, Missouri, have invented a certain new and useful Improvement in Adjusting Mechanism for Crushers or Pulverizers, of which the following is a full, clear, and exact description, such as will enable others skilled in the art to which it appertains to make and use the same, reference being had to the accompanying drawings, forming part of this specification, in which—

Figure 1 is a longitudinal sectional view through the front portion of my improved machine. Fig. 2 is a side elevational view of the front portion of said machine. Fig. 3 is a sectional view through the gear housing at the side of the machine. Fig. 4 is a sectional view of a modified form. 20 My invention relates to a new and, useful improvement in crushers and pulverizers for disintegrating materials of various kinds and particularly to the means for adjusting the breaker plate and that portion of the 25 grinding cage connected thereto.

In the drawings: 1 indicates the side framing of the machine, and 2 the front wall thereof.

3 indicates a hopper plate through whose 30 opening 3^a the material to be operated upon by the machine is fed. As the material is fed into the machine it drops upon a breaker plate 4 pivoted at 5. The material rolling down the breaker plate will be struck by the 35 revolving hammers or beaters 6 pivotally mounted upon the hammer supports 7 which are strung on a shaft 8. Below the breaker plate is a grinding surface 9, said grinding surface being movable with the breaker 40 plate. Lugs 10 extend from the lower end of the breaker plate frame on each side of the machine, in which lugs is mounted a shaft 11. Links 12 connect the shaft 11 with a shaft 13, whose ends pass through inclined 45 slots 2^a in the side frames 2. The outer ends of shaft 13 are flattened, as shown in Figs. 2 and 3 and carry inserted in the flattened portions threaded rods 14 which rods have threaded connection with a worm wheel 50 15 mounted in a gear housing 16 secured to the side frame 2. The hub of this worm wheel 15 acts as a nut and being confined between the walls of the gear housing will, when rotated, raise or lower the shaft 13 55 in its inclined slots and move the grinding

surface 9 toward or from the striking point of the hammer to take up wear of the latter.

The means for rotating the gears 15 on each side of the machine in unison, consists of worms 17 mounted in the gear housing 60 16 and meshing with the gears 15. The worms 17 are on the ends of shafts 18, one of which carries a hand wheel 19 and is geared to the other by means of a chain 20 passing over sprockets 21. 65

By the above construction, when the hand wheel 19 is turned, the breaker plate and its carried grinding surface 9 can be adjusted as desired.

In Fig. 4, I have shown a modified form 70 in which the rod 11 is connected by a link 12 to a shaft 13 mounted to slide in inclined openings 2^b in the side walls of the casing. The rod 14^a carried by the shaft 13 in this modified construction has threaded engagement with the hub of a work gear 15^a mounted in gearing housing 16^a and with which worms 17^a on a shaft 18^a co-operate. The shaft 18^a extends transversely of the machine and is mounted in suitable bearings in 80 the side frames 2, and is preferably provided with a handle at one end, not shown, by which the shaft and its carried worms may be rotated and the threaded rod 14^a moved longitudinally to effect the adjustment of the grinding surface. 85

What I claim is:

1. In a machine of the character described, the combination of a framing having slots in its side walls, a rod slidably mounted 90 in said slots, a movable member, links pivotally connected to said movable member and to said rod, threaded members carried by said rod, worm gears with which said last mentioned members have threaded engagement, a gear housing for said worm gears, and means for rotating said worm gears.

2. In an article of the class described, in combination a casing provided with guide slots, a shaft slidably mounted in said 100 slots, a movable member, links pivotally connecting the ends of the shaft with the movable member, the disposal of said slots being such as to form bearing surfaces for said shaft when pressure is applied to said movable member.

3. In a device of the class described, walls provided with guide slots, a movable member, a shaft slidably mounted in said guide 105 slots, pivoted links connecting said shaft 110

with said movable member, a screw threaded member mounted in said shaft, a screw threaded wheel coöperating with said screw threaded member, a casing abutting both sides of said wheel, and means for rotating said wheel to shift said screw threaded member longitudinally and oscillate said movable member.

4. In a device of the class described, supports provided with guiding slots, a movable member, a shaft slidably mounted in said guiding slots, pivoted links connecting said

shaft and said movable member, a threaded rod for moving said shaft in said slots, the disposal of said slots being such that pressure upon the movable member forces the shaft against the side of the slots. 15

In testimony whereof I hereunto affix my signature in the presence of two witnesses, this 2nd day of August, 1911.

MILTON F. WILLIAMS.
